UNITED STATES PATENT OFFICE.

JOHN L. SCHAFFERT, OF WASHINGTON, DISTRICT OF COLUMBIA, ASSIGNOR
OF ONE-HALF TO THOMAS MARTIN, OF SAME PLACE.

EAVES-TROUGH.

SPECIFICATION forming part of Letters Patent No. 274,393, dated March 20, 1883.

Application filed January 22, 1883. (No model.)

To all whom it may concern:

Be it known that I, JOHN L. SCHAFFERT, a citizen of the United States, residing at Washington, in the District of Columbia, have invented new and useful Improvements in Eaves-Troughs for Buildings, of which the following is a specification.

This invention has for its object to provide a novel and efficient eaves trough or gutter for buildings, which is so covered and protected as to prevent the accumulation of snow, leaves, and other débris therein, and which is of such construction that it can be uncovered for the purpose of gaining free access to the same for any purpose, such as removing débris carried into it from the roof, or to permit the rays of the sun to fall directly therein to melt ice, if such should be formed.

The object of my invention is accomplished in 20 the manner hereinafter described and claimed, and illustrated in the accompanying drawings, in which—

Figure 1 represents a sectional perspective view of my invention applied to the eaves of 25 a building, the trough or gutter being covered; and Fig. 2 is an end view of the trough and cover, showing the roof in section, the cover of the trough being closed as in full lines and open as in dotted lines. Fig. 3 is a detail view.

The trough or gutter 1 is of any usual or desirable construction, and is supported horizontally along the eaves by metallic or other brackets 2, which are constructed with a portion, 3, conforming to the under side of the trough 30 or gutter, and a shank, 4, secured to the roof by nails 5, or any other fastening device found suitable for the purpose. As shown, the bracket is set in a slot, 6, provided in the edge 7 of the roof, in such manner that when 35 the brackets and trough are in position the edge of the roof will project over the trough or gutter; but this mode of applying the supporting-brackets is not indispensable, it being, however, desirable in order to insure all drippings being caught by the trough. The outer 40 edge, 8, of the trough is further sustained by a brace-bar, 9, riveted or otherwise secured at one end to the outer end of the bracket, as at 10, and at the other end attached to the 45 bracket, as at 11, in any suitable manner. To

the outer longitudinal edge of the trough or gutter is hinged or pivoted a cover, 12, preferably of a shape conforming to the trough or gutter, the inner free edge of said cover resting in grooves 13, formed in metallic blocks 55 14, which are provided with a stud, 15, passed through an opening in the shank of the bracket and riveted in place. Several or all of the supporting-brackets are provided with these blocks, upon which the inner edge of the cover rests in such manner that the longitudinal edge of the cover is supported away from the building to permit the free passage of water from the roof to the trough. The cover is confined in its closed position to protect the 65 trough by a pivoted hook, 16, adapted to engage an aperture, 17, in one or more of the blocks 14.

The hinged connection of the two sections comprising my improved eaves-trough is preferably of such construction that the cover, when thrown open, will not fall clear around, but will be sustained in position, as shown by dotted lines, Fig. 2, so as to be within convenient reach when it is desirable to close it.

The blocks 14 need not necessarily be attached to the brackets, as they could be secured to the roof or even to the edge of the cover itself, and, if found suitable, these blocks could be dispensed with and the edge of the cover rest 80 upon the brackets, which, projecting slightly above the plane of the roof, would sustain the edge of the cover away from the roof, and provide a space for the passage of the water to the trough.

If desired, the cover can be secured in its closed position by fastening devices other than the pivoted hooks. The trough and cover may be of any form in cross-section suitable for the conditions required. The cover can be made 90 in sections, so that one section can be opened independently of the others; and, finally, the two sections could be hinged together along their longitudinal edges instead of their outer edges, as here shown.

The cover-section of the trough will usually be made of sheet metal—such as tin—and will be interiorly braced by arched plates 18, and the whole will constitute a strong and durable structure, providing an eaves-trough which 100

can be entirely covered and protected to prevent the accumulation therein of snow and leaves, except as such pass down the roof under the edges of the cover, which latter can 5 be readily thrown open to uncover the trough for the purpose of cleaning the same.

An eaves-trough has heretofore been provided with a fixed covering; but so far as I am aware an eaves-trough has never been composed of two sections hinged or pivoted together along their longitudinal edges, as hereinbefore described.

It will of course be obvious that the hinged section will cover and protect the upper end 15 of the usual downspout to prevent its being clogged up by an accumulation of leaves or other débris.

Having thus described my invention, what I claim is—

An eaves-trough or gutter composed of two 20 sections hinged or pivoted together along their longitudinal edges, one section serving to receive the water from the roof and the other as a protecting-covering, substantially as described.

In testimony whereof I have hereunto set my hand in the presence of two subscribing witnesses.

J. L. SCHAFFERT.
